Attorney.

UNITED STATES PATENT OFFICE

CHARLES E. MINCEMOYER, OF MILTON, PENNSYLVANIA, ASSIGNOR OF ONE-HALF TO
CARL E. HECHT, OF MILTON, PENNSYLVANIA

KNITTING MACHINE

Application filed January 30, 1929. Serial No. 336,131.

The object of the invention is to provide improvements in knitting machines, and particularly in an attachment which is applicable to revolving cylinder, (circular) or revolving cam (stationary cylinder) machines upon which hosiery, undervests, and the like, are knitted.

More specifically, the object is to provide one or more attachments for such machines, whereby a particular effect is obtained in the finished product, such as the provision of vertical stripes and/or designs at predetermined positions and of any desired number and width, the resulting stripe, stripes and/or designs constituting a reinforcement of the knit structure, as well as creating an enhanced appearance by means of what is known as a wrap stitch.

Referring to the means for carrying out the object thus broadly stated, a rotary yarn guide is mounted upon a revolving support above the plane of the needles, together with a relatively stationary rack or other suitably formed element, whereby said guide, which is normally fixed with respect to said support, upon encountering said element is itself rotated independently of its support, with the result that for a relatively brief portion of its circular path it describes a planetary motion, and in so doing carries the yarn around the upper portions of as many needles as may be desired, and again remains fixed until it again encounters said element.

With the foregoing facts in mind, the invention comprises further details of construction and operation such as are clearly brought out in the following description, when read in conjunction with the accompanying drawings in which Fig. 1 is a side elevation of one embodiment of the invention, showing the rack element in vertical section; and Fig. 2 is a horizontal section on the line 2-2 of Fig. 1.

Referring to the drawings, a portion of any suitable type of knitting machine is shown as comprising a suspended rotary shaft 1, to which is adjustably secured in any desired manner a yarn rack 2, upon which is supported any desired number of the usual 50 yarn cones 3, protected by inverted glass

covers 4 (or the usual yarn spiders or racks), each of which has an opening 5 in its upper portion through which the yarn 6 is adapted to freely pass from the adjacent cone through a porcelain tube 7 or the like, carried by said rack, whence the yarn proceeds downwardly towards the yarn feed attachments described below.

The shaft 1 extends through the rack 2 and to its lower free end is adjustably and removably secured, by means of a set screw 8, a circular disc 9, which it is to be understood rotates in synchronism with the cylinder 10 surrounding the usual circular row of needles 11.

The disc 9 is provided with as many bores 12 as may be desired and within each of these bores is removably secured, as by a lock nut, screws, or the like, a cylindrical tube 13, to which is secured a suitable length of capillary tubing 14, made of copper or any other non-corroding material, said tube extending downwardly and thence radially outwardly in a diagonal direction and thence downwardly in a direction substantially parallel 75 with the axis of the tube 13, as shown in Fig. 1. The tubes 13 are preferably of different lengths so as to support at different heights above the disc 9 their respective star wheels 15, having apertures 16 in alignment with the bores of the tubes 13, or said star wheels and tubes may be integrally formed of a single piece if desired. Each star wheel preferably also comprises a cylindrical surface 17, which is normally engaged by a suitably tensioned leaf spring 18 or the like, the opposite end portion 19 of which is secured in any suitable manner to a cylindrical portion of the disc 9.

Laterally positioned with respect to said disc and in alignment with the circular paths of said star wheels is a relatively fixed rack or the like 20, having a series of teeth 21 of any desired shape and in number equal to the number of teeth with which said star wheels are provided, or a multiple of such number. This rack is operatively positioned by means of any suitable support and guide 22, and with respect to such support said rack slides up and down in synchronism with 100

the rotation of the cylinder 10 by means of any suitable mechanism, as for instance by means of a cam connected with the driving shaft of the machine.

5 When the attachment is applied to a revolving cam machine, the rack 20 with teeth 21 revolves with the cam or cams, and the cylinder 10, disc 9, yarn rack 2, etc., remain stationary.

10 There may be employed as many of these improved yarn feed devices as may be desired, or as may be practicable, depending upon the type and design of machine which may be involved. The disc 9 with its supporting drive shaft 1 and yarn rack 2 may be rotated by any suitable mechanism which may comprise either the same or different means than that which rotates the cylinder 10. Also, the respective guide tubes 13 and 15 may be withdrawn and replaced whenever necessary or desirable for repair or substitution by simply lifting them upwardly and free from the bores 12 in the supporting disc 9, after first loosening the nuts or screws 20 by which they are operatively secured in position.

In the operation of the invention, the knitting machine is operated in the usual manner, but the yarn 6 passes to the needles

30 through the improved rotary guides, so that as a given star wheel encounters the teeth of the rack 20, said wheel is caused to make at least a complete revolution and thereby carry the yarn from its depending free end 35 portion in a complete wrap around all of the needles which may be in raised position at a predetermined point in the circular needle row, or in the path of the arc of needles as the latter are being raised and lowered out of their normal position of rest. Through 40 each of these rotatable yarn feeds can be passed a different type of yarn or silk thread, or as many different colors as may be desired, either singly or in multiple, so that as many 45 stripes or other possible designs are produced in the finished knit product as there are rotary feeds.

Having thus described my invention, what I claim and desire to protect by Letters Patent of the United States is:—

50 1. The combination of a knitting machine comprising a cylinder of needles and a support rotatable in synchronism therewith, with a yarn guide rotatably carried by said support upon an axis eccentric to the axis of said support and comprising a toothed head having a central bore and a tube communicating with said bore and having its free end terminating laterally of its axis of rotation 55 60 with respect to said support and below the level of the upper ends of said needles when they are in raised position, a relatively stationary toothed rack adapted to engage and rotate the toothed head of said guide with respect to said support and to said needles

while in a predetermined portion of its path or orbit, to cause yarn from the free end of said guide tube to encircle a predetermined set of needles, and resilient frictionally braking means engaging and limiting the rotation of said head with respect to said support to only the movement imparted thereto by said rack. 70

2. The combination of a knitting machine comprising a cylinder of needles and a support rotatable in synchronism therewith, with a yarn guide rotatably carried by said support upon an axis eccentric to the axis of said support and comprising a head having a central bore and a tube communicating with said bore and having its free end terminating laterally of its axis of rotation with respect to said support, means to rotate said head of said guide with respect to said support and to said needles while in a predetermined portion of its path or orbit, to cause yarn from the free end of said guide tube to encircle a predetermined set of needles, and resiliently frictionally braking means engaging and limiting the rotation of said head with respect to said support to only the movement imparted thereto by said first means. 85

In testimony whereof I have affixed my signature.

CHARLES E. MINCEMOYER.
